UNITED STATES PATENT OFFICE.

FRANCIS T. LEEDER, OF SIOUX CITY, IOWA.

BRICK-CLEANING MACHINE.

SPECIFICATION forming part of Letters Patent No. 779,224, dated January 3, 1905.

Application filed June 23, 1904. Serial No. 213,850.

To all whom it may concern:

Be it known that I, FRANCIS T. LEEDER, a citizen of the United States, residing at Sioux City, in the county of Woodbury and State of Iowa, have invented new and useful Improvements in Brick-Cleaning Machines, of which the following is a specification.

This invention relates to brick-cleaning machines, and aims to provide a machine of such character with new and novel means for cleaning bricks.

Primarily the invention resides in the construction of the cleaning-heads of the machine, together with a means for imparting uniform pressure to the heads, so that the heads will bear against the bricks in a uniform manner during the cleaning operation and which will compensate for the varying thicknesses of the mortar carried by the bricks.

The invention further aims to provide the cleaning-heads with raised cutting portions or teeth which facilitate the removal of the mortar from the bricks during the passage of the latter between the cleaning-heads.

With the foregoing and other objects in view the invention aims to construct a machine of the class referred to which shall be simple in its construction, strong, durable, efficient in its use, and comparatively inexpensive to set up; and to this end the invention consists of the novel combination and arrangement of parts hereinafter more specifically described, illustrated in the accompanying drawings, and particularly pointed out in the claims hereunto appended.

In describing the invention in detail reference is had to the accompanying drawings, forming a part of this specification, and wherein like reference characters denote corresponding parts throughout the several views, and in which—

Figure 1 is a top plan view of a brick-cleaning machine embodying the novel features of this invention. Fig. 2 is a section on line 2—2 of Fig. 1, and Fig. 3 is an elevation of the working face of one of the cleaning-heads.

Referring to the drawings by reference characters, 1 denotes the feed-table, having a longitudinally-extending opening 2 to permit of the operation of the conveyer-blocks 3, car-

ried by the conveyer 4. The latter at one end travels over a pulley 5, mounted upon a shaft 6, suitably journaled in the table, while the other end of the conveyer is connected to an operating means therefor. (Not shown.) The 55 conveyer-blocks 4 are adapted to pass between the cleaning-heads, to be hereinafter referred to.

Mounted upon the feed-table 1 is a series of longitudinally-extending supporting members 7, 8, and 9, the members 7 and 9 being arranged at the sides of the table 1, and the member 8 is interposed between the members 7 and 9. Adjustably secured through the medium of a slot-and-bolt connection 10 to the 60 supporting member 9 is a longitudinally-extending guide-bar 11, which is arranged parallel with the path of the conveyer-blocks, and adjustably secured to the member 8 through the medium of a slot-and-bolt connection 12 is 65 a guide 13, which extends a portion of its length parallel with the path of the conveyer-blocks and has its rear end curved outwardly, as at 14. The guides 11 and 13 are adapted to retain and guide the bricks in position to 70 toward the cleaning-heads, to be hereinafter referred to.

Journaled in the members 7 and 8 and extending in a transverse direction is a rotatable and transversely movable or yielding shaft 80 15, carrying a gear or band wheel 16, which is suitably connected with means for imparting movement thereto, thereby rotating the shaft 15. The outer end of the shaft 15 is engaged by a head 17, carried on the forward 85 end of an adjustable regulating-lever 18, the latter being pivoted to the member 7, as at 19, and has extending therethrough intermediate its length a regulating-pin 20, screw-threaded at its outer end, as at 21, and upon said outer 90 end 21 is mounted a regulating-bur 22. The regulating-pin 20 passes through an eye 23 and has its inner end provided with a head 24. Between said eye and head is mounted a tension-spring 25 upon the pin 20, whose tension 95 is increased or decreased through the medium of the regulating-bur 22—that is to say, if the bur is rotated in one direction the tension of the spring will be increased, or if the bur is operated in the other direction the tension 100

is decreased. The bur 22 is provided with a shoulder 26, which is engaged by a lock-screw 27, so that the bur may be held in any desired position.

of the spring will be diminished. The pin loosely extends through the regulating-lever 18, and through the connection between the shaft 15 and said lever 18 said shaft 15 is 5 yieldingly mounted, so as to compensate for different thicknesses of mortar upon the bricks when the said bricks are passing between the cleaning-heads, to be hereinafter described, for the reason that one of the 10 cleaning-heads is carried upon the inner end of the shaft 15.

The reference character 26 denotes a transversely-extending shaft which is journaled in the member 9 and carries a gear-wheel or 15 band-pulley 27, which is connected to a suitable means for imparting movement to said shaft 26. The transversely-extending shaft 26 may be transversely movable or yielding in the same manner as the shaft 15, and if so 20 the adjustable lever and its connection are attached to the shaft 26 in the same manner as the shaft 15. In some cases it has been found advisable to make one of the shafts rotatable and yielding and the other shaft simply rotatable 25 and not transversely movable or yielding, and in some cases it has been found necessary to make both of the said shafts transversely movable or yielding in a manner as set forth. One of the shafts is shown yielding 30 through the medium of the adjustable lever and its connections; but it is evident that both of said shafts can be made transversely movable; but the adjustable lever and its connection are simply shown as applied to one of 35 the shafts.

The inner end of the shaft 15 carries a cleaning-head, and the inner end of the shaft 26 carries a cleaning-head. These cleaning-heads are opposed to each other and are arranged 40 at the side of the path of the conveyer-blocks 3. As both of the cleaning-heads are constructed alike, but one will be described, the same reference characters being applied to both heads. Each of the cleaning-heads is 45 mounted for rotation upon its respective shaft and is provided with a hub secured to its respective shaft in any suitable manner. Each of the cleaning-heads consists of a disk 28, having one face provided centrally with a concentric series of beveled teeth 29, which are 50 grouped in close proximity to each other, and the same face of the disk is further provided throughout with a series of beveled teeth 30, arranged promiscuously and suitably spaced 55 apart. The teeth 29 are somewhat longer than the teeth 30. The teeth are so constructed as to form the toothed face of each cleaning-head in a convexed manner—that is to say, the teeth gradually increase in height from the 60 outer edge of each disk to the center thereto. The arrangement of the teeth in such a manner allows for the gradual decreasing thickness of the brick as the mortar is being removed and as the brick passes between the 65 two cleaning-heads.

The reference character 31 denotes the hub, which is an integral portion of the disk and which is suitably fixed to its respective operating-shaft.

By providing the adjustable lever and its 70 spring connection for the shaft 15 or for the shafts 15 and 26 the cleaning-heads press against the bricks in a uniform manner, and consequently the heads are yielding, so as to compensate for the varying thickness of the 75 mortar upon the bricks.

Of course it will be evident that in assembling the brick-cleaning machine three groups of heads would be employed—one to clean the side, another the end, and the other the edges 80 of the bricks—and all that would be necessary would be to arrange the heads with respect to the conveyer at different parts of the feed-table, the operator turning the brick in the proper manner after it passes through one 85 pair of cleaning-heads.

When it is desired to clean a brick, it is shoved up against the guide 11, and as the conveyer is traveling toward the cleaning-heads one of the conveyer-blocks will engage 90 the brick and carry it forward to the cleaning-head. During the passage of said brick toward the cleaning-heads the guide 13 will also assist in retaining it in position. When the brick reaches the cleaning-heads, the teeth 95 of the heads will operate upon the brick to clean the mortar therefrom, and owing to the arrangement and peculiar construction of the teeth, as shown, the mortar will be readily removed from the bricks during the rotation of the cleaning-heads, or, in other words, the teeth will in reality cut the mortar very rapidly from the brick. Owing to the arrangement of the regulating means with respect to one or both of the shafts, the heads will bear 100 in a uniform manner against the bricks, and as the teeth eat down into the mortar the regulating means will gradually move the heads toward one another, so as to keep the teeth in the proper position with respect to the mortar, so that all of it will be removed from the 110 bricks.

It is thought the many advantages of a brick-cleaning machine embodying the cleaning-heads constructed in accordance with the foregoing description and also embodying the transversely-movable shaft or shafts which carry the cleaning-heads as set forth can be readily understood, and it will furthermore be evident that changes, variations, and modifications can be resorted to without departing from the spirit of my invention or sacrificing any of its advantages, and I therefore do not wish to restrict myself to the details of construction hereinbefore described, and set forth 115 in the annexed drawings, but reserve the right to make such changes, variations, and modifications as come properly within the scope of the protection prayed.

Having thus fully described my invention, 130

what I claim as new, and desire to secure by Letters Patent, is—

1. A brick-cleaning machine having a pair of rotatable cleaning-heads, each comprising a disk having one face provided with a concentrically-arranged series of cutting-teeth at the center thereof, grouped in close proximity to each other and further provided with a plurality of cutting-teeth irregularly disposed throughout said face.

2. A brick-cleaning machine having a pair of rotatable cleaning-heads, each comprising a disk having one face provided with a concentrically-arranged series of cutting-teeth at the center thereof, grouped in close proximity to each other and further provided with a plurality of cutting-teeth irregularly disposed throughout said face, each of said cleaning-heads being substantially convexed in cross-section.

3. A brick-cleaning machine having a pair of rotatable cleaning-heads, each comprising a disk having one face provided with a concentrically-arranged series of teeth at the center thereof and further provided with a plurality of beveled cutting-teeth irregularly disposed throughout said face.

4. A brick-cleaning machine having a pair of rotatable cleaning-heads, each comprising a disk having one face provided with a concentrically-arranged series of cutting-teeth at the center thereof, and further provided with a plurality of beveled cutting-teeth irregularly disposed throughout said face, each of said cleaning-heads being substantially convexed in cross-section.

5. A brick-cleaning machine comprising a pair of cleaning-heads, each provided on one face with a closely-arranged concentric series of cutting-teeth and further provided with beveled cutting-teeth irregularly disposed throughout said face, a rotatable operating-shaft for each of said disks, one of said shafts being transversely movable, and an adjustable yielding regulating means for said transversely-movable shaft.

6. A brick-cleaning machine comprising a pair of rotatable cleaning-heads, a rotatable shaft fixed to each of said heads, one of said shafts being transversely movable, an adjustable regulating-lever engaging the outer end

of said transversely-movable shaft, and an adjustable and yieldable regulating-pin for said lever.

7. A brick-cleaning machine comprising a pair of cleaning-heads, each provided with a concentrically-arranged series of teeth and an irregularly-arranged series of teeth, rotatable means for said heads, and an adjustable yieldable regulating means for said rotatable means.

8. A brick-cleaning machine having a pair of cleaning-heads, each of which consists of a disk, a hub connected with the disk, a concentric series of beveled teeth grouped in close proximity to each other and arranged approximately centrally of one face of the disk, and further provided with an irregularly-arranged series of beveled teeth on said face and extending from the edge of the disk to near the concentrically-arranged series of teeth.

9. A brick-cleaning machine having a pair of cleaning-heads, each of which consists of a disk, a hub connected with the disk, a concentric series of beveled teeth grouped in close proximity to each other and arranged approximately centrally of one face of the disk, and further provided with an irregularly-arranged series of beveled teeth on said face which extend from the edge of the disk to near the concentrically-arranged series of teeth, each of said heads substantially convexed in cross-section.

10. A brick-cleaning machine comprising a pair of rotatable toothed cleaning-heads, a rotatable shaft fixed to one of said heads, a rotatable and transversely-movable shaft fixed to the other of said heads, an adjustable regulating-lever pivoted at one end and having its other end engaging the outer end of said transversely-movable shaft, an adjustable and yielding regulating-pin extending through said lever, and means mounted upon the outer end of said pin for adjusting it, thereby regulating the movement of said lever.

In testimony whereof I have hereunto set my hand in presence of two subscribing witnesses.

FRANCIS T. LEEDER.
